CHINA DISPLAY STAND

Leonard Naomi Hashimoto, 2816 S. Hauser Blvd.,
Los Angeles, Calif. 90016

Filed Mar. 25, 1968, Ser. No. 11,106

Term of patent 14 years

Int. Cl. D6—01
U.S. Cl. D80—9

FIG-2

I claim:

The ornamental design for a china display stand, substantially as shown.
